UNITED STATES PATENT OFFICE.

ROMAN H. MALICKI, OF CHICAGO, ILLINOIS.

ELECTRICALLY-CONTROLLED COMBINATION MECHANISM FOR LOCKS.

Application filed April 18, 1925. Serial No. 24,283.

This invention relates to new and useful improvements in locks and more particularly to an electrically operated combination mechanism for locks. The main object of my invention is the provision of an electrically controlled combination mechanism wherein a predetermined selective combination is actuated for releasing the locking member, said locking member being automatically released upon the completion of the selective combination.

Another object of my invention is the provision of an electrically operated combination mechanism which employs a selective combination and wherein the actuating parts are automatically returned to their normal positions, should a person operating the lock make an error in carrying out the combination so that the person can again start at the beginning of the selective combination to properly operate the mechanism.

A further object of my invention is the provision of an electrically operated combination mechanism which may be applied to doors of residences, vaults and other places where it is desired to normally retain the door in a locked position and wherein access can only be gained through the door by an authorized person who is in possession of the proper combination for actuating the lock.

A still further object of the invention is the provision of an electrically operated combination mechanism for locks which when applied to the door of a residence will have the means for controlling the selective combination located upon the exterior of the door so that a party in possession of the proper combination may readily enter and has in connection therewith an audible signal to be sounded upon the interior of the residence and is further provided with a single actuating mechanism whereby a party upon the interior of the residence may actuate the lock independent of the selective mechanism.

A still further object of my invention is the provision of a combination mechanism including electrically operated combination control cooperating with an electrically operated registering means whereby the selective combination may be carried out through the actuation of the consecutive operation of the combination and registering mechanism for completing the selective combination and automatically releasing the lock.

With the above and other objects in view,

my invention consists in the novel features of construction and the combination and arrangement of parts to be hereinafter more fully described, pointed out in the claim 60 in which:

Fig. 1 is an elevation of the combination mechanism employed,

Fig. 2 is a similar view looking from the 65 opposite direction to the showing in Figure 1,

Fig. 3 is a transverse section taken on the line 3—3 of Figure 1,

Fig. 4 is a transverse section taken on the 70 line 4—4 of Figure 2,

Fig. 5 is a detail elevation of the mechanism illustrating the same in one of its advanced positions,

Fig. 6 is a similar view showing the mechanism in its completely advanced position for 75 actuating the locking mechanism,

Fig. 7 is a side elevation of the reciprocating rack,

Fig. 8 is an edge elevation of the mechanism, 80

Fig. 9 is a detail transverse section of the circuit closing member,

Figures 10, 11 and 12 are detail perspective views of different parts of the device, 85 and

Figure 13 is a diagrammatic view.

In putting my invention into practice, it is preferred to have the operating mechanism supported upon the door casing and 90 further, if desirable, may be located between the walls of a building so as to be entirely out of sight with means for gaining access to the same in case the device should need repairing, and the main operating mechanism 95 is supported upon a bracket 1 which is provided with openings 2 whereby screws, bolts or the like may be used for retaining the bracket in position upon a suitable support.

The bracket has attached to its upper face an upright body plate 3 which is securely attached to a vertically disposed lug 4 upon the upper face of the bracket 1 and the longitudinal edges of the body plate are disposed at right-angles to the plate as shown at 5 to form a complete rigid support for the body plate. The body plate 3 carries a pivot pin 6 upon which is mounted a rockable member 7 having a curved portion 8 and an arm 9 extending from the end of the curved portion forming a guide for the rack 10. Extending laterally from the outer end of

the curved portion 8 and from the body of the member 7 are the spaced perforated ears 11 and slidably mounted within these ears is a guide rod 12, the upper end of which is connected to a lateral finger 13 carried by the rack 10 to properly guide the movement of the rack and retain the same against one edge of the arm 9.

Mounted upon the body plate 3, adjacent the upper end thereof, is a solenoid 14, the pole 15 of which has its lower end movable through a guide 16 and mounted upon the pole 15 is a bell crank 17 one end of which projects through a slot 18 in the body plate 3 while the other end thereof is engaged with the teeth 19 on the rack 10. When the pole 15 is in its projected position, the end of the bell crank which extends through the slot 18, is engaged with a shoulder 20 on one side of the slot to normally maintain the arm 21 of the bell crank out of engagement with the teeth 19. As the pole 15 of the solenoid 14 moves into the solenoid, the arm 22 of the bell crank will ride off of the shoulder 20 through the tension of the coil spring 23, causing the arm 21 to engage with the teeth 19 and reciprocate the rack 10 relative to the arm 9, the length of movement of the rack being equal to the distance between the teeth, and the rack is retained against returning movement by means of a U-shaped pawl 24 pivotally mounted upon the outstanding ear 25 formed by stamping the same from the body plate 3. The arm 26 of the U-shaped member 24 rides over the teeth 19 and engages with the same to retain the rack 10 in a raised position so as to permit the arm 21 to be actuated as above. The rack 10 is normally retained in its lowermost position as shown in Figure 1 by means of a coil spring 27, the lower end of which is attached to the bracket 28 on the rockable member 7 while the upper end is attached to the finger 13 on the rack.

The base plate is provided in the body thereof with an opening 29 behind which is arranged an insulated plate 30 having a plurality of longitudinal rows of spaced threaded openings 31. These openings in the plate 30 are preferably arranged longitudinally and in transverse alignment, as illustrated for receiving the pins 32, the pins being arranged in predetermined openings in accordance with the selective combination to be carried out. The solenoid 14 is electrically connected to a push button 33 so that when this button 33 is pressed inwardly to energize the solenoid 14 the pole 15 thereof is moved into the solenoid, moving the bell crank 17 laterally with the arm 21 in engagement with one of the teeth 19 on the rack 10, this operation moving the rack 10 over the plate 30, a distance equal to that from the bottom of the plate 30 to the first pin 32 in the first longitudinal row so that the notch 34 in the

rack will align with this pin. The rockable member 7 is then moved upon its pivot, moving the rack laterally so that the pin will pass through the notch 34 to the opposite side of the rack and permit the rack to drop downwardly again to its lowermost position. 70

Pivotedly mounted upon the pin 35 and arranged upon the opposite face of the base plate 3 from the rockable member 7 is an arm 36 carrying a pivot pin 37 at one end and 75 a pivot pin 38 at the other end. Mounted upon the pivot pin 37 is a curved arm 39, having a finger 40 projecting at right-angles to the arm and extending through an opening 41 in the base plate for engagement with 80 the teeth 42 formed on one edge of the rockable member 7.

A solenoid 43 is carried by the base plate 3 diagonally opposite the solenoid 14, the pole 44 of which is attached to the reciprocating arm 45, said arm having an angular guide plate 46 provided with a slot 47 which received the guide pin 48 carried by the base plate 3 and projecting upwardly from the guide plate 46 is a finger 49 having a hook 50 at its upper end. The lower end of the arm 45 has a horizontal plate 51 attached to the outer end of the pole 44 and has a lug 52 which extends through a slot 53 in the base plate 3 and engages one end of a pivoted bar 54 which is mounted on the pivot pin 38 which is carried by the arm 36. The arm 36 is retained in a normal position by means of a coil spring 55 which is connected to one end of the arm as shown at 56 and to a lug 57 at the lower end of the base plate. The arm 36 is retained in a relatively normal position and is governed through the movement of the bar 54, one end of which engages the inner end of the pivot pin 37 100 while the other end is in direct contact with a lug 52 which bears against a shoulder 58 formed in one side of the slot 53. 105

In operating my improved combination mechanism, the push button 33 is to be actuated the proper number of times in accordance with a pre-determined selective combination. In the present instance, the combination is "1, 3, 7 and 9", thus the party desiring to open the door presses the registering button 33 inwardly to energize the solenoid 14, moving the pole 15 inwardly to thus impart a lateral movement to the bell crank 17 which will cause the arm 21 to engage one of the teeth 19 on the rack 10 and move the rack upwardly a distance equal to the longitudinal distance between the openings 31 so that the notch 34 in the rack 10 will be in direct alignment with the lowermost pin in the right-hand longitudinal row of openings. After the above has been carried out, the combination button 59 is then pressed inwardly to cause a circuit to the solenoid 43. At this time I wish to call attention to the fact that the bell crank 17 is returned to its normal 110 115 120 125 130

lowermost position and the pole 15 drawn outwardly from the solenoid to a projected position, as shown in Figure 1, by means of the coil spring 23, the arm 26 of the U-shaped member 24 retaining the rack in a raised position. This arm 26 is retained in a normal engaging position with the teeth 19 by means of a coil spring 60 one end of which is attached to the U-shaped member 24 above its pivot point while the other is attached to the base plate 3.

After the button 59 has been pushed inwardly to complete the circuit to the solenoid 43, the pole 44 thereof is drawn into the solenoid which will move the arm 45 downwardly bringing the inclined shoulder 61 thereon into engagement with the stop lug 62 on the U-shaped member 24 so as to rock the U-shaped member upon its pivot 20 and disengage the arm 26 from the teeth 19. This movement will move the other arm 63 of the U-shaped member beneath the catch 64 on the pivoted arm 65 which carries a weight 67 at its other end, thus retaining 25 the arm 26 out of the path of the teeth 19 so as to permit the rack to drop downwardly to its normal inoperative position, the pin being behind the upwardly extending arm 68 of the rack. The button 33 is then 30 pressed consecutively three times so as to impart three separate forward movements of the rack 10 to bring the notch 34 into alignment with the pin which is in the second notch from the right at which time the button 59 is pressed to carry out the operation disclosed above, moving the rockable member 7 upon its pivot against the tension of the spring 69. At this time, I wish to call attention to the fact that as the solenoid 43 and the pole 44 move inwardly to operate the reciprocating arm 45, the downward movement of the plate 51 will cause the lug 52 to engage the bar 54 which while attached to the pivot 38 will rock 40 the arm 36 upon its pivot moving the curved arm 39 upwardly so that the finger 40 will engage with the notches 42 in the rockable member and rock the same upon its pivot 45. At this time, I wish to call attention 50 to the fact that the bar 54 is retained in a normal position by means of a spring 70 coiled upon the pivot pin 38 with one end connected to the bar and the other end engaged beneath the stop arm 71 formed on the upper end of the curved arm 39. This spring 70 is of sufficient tension to retain the bar 54 in a normal position relative to the arm 36 until the spring 55 has been placed under a certain degree of tension, 55 thus upon the continued downward movement of the arm 45 will cause the lug 52 to rock the bar upon the pivot 38.

The edge of the rockable member 7 is provided at a point above the teeth 42 with a series of teeth 72 adapted to be alternately

engaged by means of a spring retained pawl 73, thus at each operation of the solenoid 43, the finger on the curved arm 39 will rock the member 7 upon its pivot to pass one of the pins 32 through the notch 34 of the rack and as this is done, the pawl 73 engages one of the teeth 72 for retaining the rockable member in its advanced position.

After the uppermost arm 68 on the rack has passed the second pin, the button 33 is 75 depressed seven times consecutively, operating the solenoid 14 the same number of times, raising the rack 10 until the notch 34 therein is in alignment with the pin in the third longitudinal row of openings at which 80 time the solenoid 43 is again actuated as previously disclosed. For the fourth number of the combination, the solenoid 14 is energized nine consecutive times to bring the notch 34 into alignment with the uppermost pin 32 and as the rockable member 7 moves laterally upon its pivot the bracket 74 at the upper end of the arm 9 passes through the notched portion 75 on an insulated bracket 76 and engages the yieldable 85 finger 77 positioning the same outwardly in the path of the hook 50 so that as the reciprocating arm 45 moves downwardly upon energizing the solenoid 43, it engages the finger 77 and moves the contact arm 78 from the contact 79 onto the contact 80.

In order to provide means whereby the circuit between the battery 81 and the solenoid 43 will be broken, sufficiently, to permit the pole 44 to return to its normal outward position, a plate 82 is positioned upon the contact 79 at its outer edge and has a raised portion 83 over which the arm 78 rides while moving from the contact 79 to the contact 80, thus providing sufficient break 100 in the circuit to permit the pole 44 to move outwardly of the solenoid and return the arm 45 to its normally raised position. The contact 80 is connected to the automatic operating mechanism of the lock which has 105 been previously disclosed in my co-pending application filed by me April 18, 1925, for lock structure, and bearing Serial No. 24-285, thus the lock is automatically actuated through the contact of the arm 78 with 110 the contact point 80 which completes a circuit through the lock 84 and as soon as the arm 45 moves to its upward normal position the upper edge of the plate 46 will engage 115 the inner end of the arm 77 and move the arm 78 from the contact 80 back to the contact 79 beneath the plate 82, the raised portion 83 being curved on its inner face to properly guide the arm 78 onto the contact 79.

As the rockable member 7 moves laterally upon its pivot, during the actuation of the last combination number, the pawl 73 will be positioned above the tapered shoulder 85 on the sliding bar 86 which is attached to 130

the base plate 3 by the pivot pin 35 which is arranged in the slot 87 in the bar, thus when the solenoid 43 is actuated to rock the arm 36 upon its pivot, the bar 54 will be operated beyond a certain pre-determined movement of the arm 36 so that the inner end thereof will move upwardly and engage the lug 88 on the upper end of the bar 86 which projects through an opening 89 in the base plate 3, this operation moving the bar 86 upwardly over the face of the base plate 3 and cause the pawl 73 to ride over the shoulder 85 and be moved out of the path of the teeth 72 so as to permit the rockable member 7 to return to its normal position. The rockable member 7 has a projection 90 on its lower edge arranged in the path of the out-turned end 91 on the lower end of the bar 86 for engaging the same to return the bar to its normal lowered position after the rockable member returns to its normal position so that the mechanism is again ready for operation.

Should the operator become confused in pressing the button 33 the proper number of times so that the notch 34 in the rack is out of alignment with the proper pin, and presses the button 59, thus energizing the solenoid 43, it will be noted that the limit of movement of the arm 36 is prevented through the engagement of the finger 40 with the teeth 42 on the rockable member, thus permitting the bar 54 to continue in its movement and engage the lug 88 on the bar 86 to raise the bar so as to disengage the pawl 73 from the teeth 72 and permit the rockable member to return to its normal inoperative position so that the party will have to begin the operation over again. In actuating the rack 10, it will be noted that the arm 26 engages the teeth to retain the rack in its normal properly raised position while the arm 63 will engage behind the catch 64 of the arm 65 upon actuation of the reciprocating arm 45, thus retaining the arm 26 out of the path of the teeth while the rack drops to its normal position and striking the arm 65 to disengage the match 64 from the arm 63 so as to again position the arm 26 on the face of the teeth 19.

It will be apparent from the above that any authorized person knowing the combination may quickly and readily operate the mechanism to automatically release the retaining lock for the door. It will also be apparent that a great number of selective combinations may be carried out by arranging the pins 32 in various relative positions with respect to each other.

The block 92 which houses the contacts of the buttons 33 and 59 carries a button 93 which is connected upon a circuit with the battery 81 to an annunciator 94 located upon the interior of a residence, thus when a party desires to enter and does not know the combination they press the button 93 to sound the annunciator 94 at which time any person within the residence will press the button 95 which is connected in circuit with the lock 84 so as to release the lock independent of the combination mechanism.

In selecting the various combinations it will be apparent from the showing in Fig. 1 that the lower set of horizontal openings which are indicated at 91 may be used as 0 in the combination.

While I have shown and described the preferred form of my invention it will be obvious that various changes in the details of construction and in the proportions may be resorted to for successfully carrying my invention into practice without sacrificing any of the novel features of construction or departing from the scope of the appended claim.

Having thus described my invention, what I claim is:

In combination with an electrically controlled lock, of an electrically controlled selective mechanism, a pivoted switch, cooperative means between the selective mechanism and switch whereby a predetermined movement of the selective mechanism and make and break a circuit through the electrically controlled lock, and means whereby to reset said mechanism upon completion of a selective combination upon actuation of said switch.

In testimony whereof I affix my signature.
ROMAN H. MALICKI.
